UNITED STATES PATENT OFFICE.

WILLIAM A. COLLINGS, OF KANSAS CITY, MISSOURI.

SHOE MUD-GUARD.

1,242,923.

Specification of Letters Patent.

Patented Oct. 16, 1917.

Application filed May 24, 1915. Serial No. 30,001.

To all whom it may concern:

Be it known that I, WILLIAM A. COLLINGS, a citizen of the United States, and a resident of Kansas City, in the county of Jackson and 5 State of Missouri, have invented certain new and useful Improvements in Shoe Mud-Guards; and I do hereby declare that the following is a full, clear, and exact description of the same, reference being had to the 10 accompanying drawings, and to the numerals of reference marked thereon, which form a part of this specification.

This invention relates to new and useful improvements in mud guards for footwear 15 and the like, and relates more particularly to a guard adapted to prevent the lower rear edge of trousers from dropping into mud and slush, as well as adequately deflect the mud and slush from the lower portion of the 20 trousers as the wearer walks.

It is a further object of this invention to provide a mud guard which can be readily attached and detached from an article of 25 footwear with the least possible annoyance to the wearer.

The invention (in a preferred form) is illustrated in the drawings and hereinafter more fully described.

In the drawings:

30 Fig. 1 is a view showing a device embodying the invention applied to a shoe.

Fig. 2 is an enlarged view similar to Fig. 1, and illustrating the manner in which the device is attached to the heel of a shoe.

35 Fig. 3 is a section taken on line 3—3 of Fig. 2.

As shown in Figs. 1, 2, and 3 the reference numeral 1, indicates a shoe, which is provided with a sole 2, and a raised heel 3. The 40 preferred form of my invention is illustrated in said figures, and as shown, embraces an arcuate strip 4, which may be of fiber or any other suitable material, the upper edge of which projects upwardly and outwardly to afford a trouser supporting flange 5, and the lower edge is tapered to afford a downwardly and outwardly directed mud deflecting flange 6. Means are provided whereby said strip may be rigidly, but removably se- 45 cured to the heel of a shoe, embracing a relatively short and arc shaped bearing plate 7, the upper edge of which is embedded in said strip 4, and the lower edge of which is reduced to afford a flat downwardly directed

resilient tongue 8, adapted to be engaged in 55 the slot 9, of the attaching pin 10.

When it is desired to attach the device to a shoe the flat pin 10, is driven into the shoe at a point between the sole 2, and the upper lift of the heel 3, in such a manner that the 60 end having the slot 10, will only project therefrom a slight distance, as shown in Figs. 1, 2, and 3. The guard may then be quickly secured in position by engaging the resilient pin 8, in the slot 9, of said attaching pin 10, and it is held firmly in place by means of the spring shoulder on the pin 8, which engages the under side of the attaching pin 10.

It is obvious from the construction de- 70 scribed that the device, when used, will serve to greatly increase the life of the trouser fabric which it supports, for the reason that it will prevent the same from becoming im- pregnated with mud or dirt. In dry 75 weather the device illustrated in Figs. 1 to 3 inclusive may be readily detached from the shoes, and owing to their relatively small size may be carried in the pocket until it shall again become necessary to use the 80 same.

It is obvious from the construction de- 85 scribed that many details of my invention may be varied without departing from the principles of the same, and I therefore do not purpose limiting the patent granted otherwise than necessitated by the prior art.

I claim as my invention:

1. A mud guard for footwear embracing an arcuate strip, means embedded therein 90 and slotted means for receiving the same for attaching the strip to the rear of the heel of a shoe.

2. A mud guard for footwear embracing an arcuate strip provided with an upwardly 95 directed trouser supporting flange and a downwardly directed mud deflecting flange, a member embedded therein and projecting therefrom, and means adapted to be engaged by said member to secure said strip 100 to an article of footwear with said flanges spaced a distance therefrom.

3. A combined mud guard and trouser support comprising an arcuate strip pro- 105 vided with an upwardly and outwardly di- rected trouser supporting flange integral with the upper edge thereof, and a down- wardly and outwardly directed mud deflect-

ing flange integral with the lower edge thereof, a slotted member, and means adapted to releasably engage the same to mount said mud guard and trouser support on the heel of an article of wearing apparel.

4. In a device of the class described, an arcuate strip, upwardly and downwardly directed flanges integral therewith, a bearing plate partially embedded in said strip and 10 reduced at its free edge to afford a resilient

tongue, and an attaching pin having a slot therein adapted to receive said tongue and lock the same thereto.

In testimony whereof I have hereunto subscribed my name in the presence of two subscribing witnesses.

WILLIAM A. COLLINGS.
